UNITED STATES PATENT OFFICE.

JAMES N. ALLENWORTH, MOODY C. KELTNER, AND OLIN C. COLLINS, OF MEMPHIS, TENNESSEE; SAID ALLENWORTH AND SAID COLLINS ASSIGNEES TO NATHAN A. CARTER AND LUTHER WALLIN, OF EARLE, ARKANSAS.

WINCH ATTACHMENT FOR TRACTORS.

Application filed April 12, 1924. Serial No. 705,996.

Our invention relates to winch attachments for tractors.

The objects of the invention are to provide an attachment of this kind in which the weight of the winch and its operating mechanism is supported by the tractor adjacent the main traction wheels and the necessity of providing an extension platform is avoided and a rigid support for the winch obtained; to provide such a construction and arrangement of the parts of the winch supporting frame that the same may be utilized to receive and support an auxiliary winch and its frame which may be driven from the operating mechanism for the main winch; to provide a construction and arrangement by means of which either or both winches may be readily applied to or removed from the tractor; and to provide a simple, effective and comparatively inexpensive driving mechanism between the power take-off of the tractor and the winch. The invention also aims to improve generally the construction of attachments of this kind.

With these objects in view, our invention is embodied in preferred form in the construction illustrated in the accompanying drawings and set forth in the following specification.

In these drawings—

Fig. 1 is a plan view of a part of a tractor showing our improved winch applied thereto;

Fig. 2, an enlarged side view in elevation;

Fig. 3, a rear view;

Fig. 4, a longitudinal vertical section through one of the winch drums and its driving parts;

Fig. 5, a detail side elevation of one of the side members or brackets of the winch carrying frame;

Fig. 6, a bottom plan view of the member shown in Fig. 5; and

Fig. 7, a rear end view of the right hand member or bracket of said frame.

Referring to the drawings, a tractor of the well known Fordson design is in part illustrated and 1 indicates the gear and axle housing of such tractor. Clamped to each end of the axle housing is a longitudinally extending arm 2 forming part of an integral side member or bracket of a supporting frame in which the winch and its operating mechanism are adapted to be mounted. This

arm has a curved surface at its forward end 55 which bears upon the cylindrical end portion of the axle housing and a detachable clamp member 3 embraces the axle housing and is secured by nuts to the arm 2 in order to thereby rigidly but detachably secure the 60 arms directly to the axle housing. The arms 2 at their rear ends are integral with depending arms 4. These arms at their lower ends are provided with flanges 5 adapted to be supported on and be bolted to a cross bar 65 6 bolted to and forming in effect a part of the draw bar 7 of the tractor. By this arrangement, the entire weight of the frame and the winch and its operating mechanism is disposed on the tractor structure proper 70 between the axle and the end of the draw bar. Also the housing and the draw bar serve as cross connecting members for the side members of the winch frame.

The winch is adapted to be driven from 75 the usual power take-off shaft of the tractor. This shaft is indicated at 8 and on which is mounted a sprocket 9, driving chain 10 which drives the large sprocket wheel 11 carried by the shaft 12 which is mounted in 80 bearings 13 carried by the arms 2 of the side members. This shaft carries a pinion 14 meshing with a larger gear wheel 15. Bolted to this gear wheel 15 are annularly disposed laterally projecting tapered wooden blocks 85 16 (see Fig. 4) which project into tapered apertures or recesses 17 formed by members projecting from the flange 18 of the winch drum. This flange is integral with the barrel 19 of the winch and also formed integral 90 with said flange is a bearing sleeve 20. The wooden blocks serve as friction drive means between the driven gear wheel 15 and the winch drum and they are adapted to be connected and disconnected from the latter by 95 shifting the drum laterally on its shaft. This movement is effected by a threaded thrust nut 21 which is threaded upon one end of a sleeve 22 fixed to the frame in which the winch is mounted. On the end of the shaft outside of the frame member is keyed 100 a thrust collar 23. An adjustable clamp member 24 surrounds the thrust nut 21 and is provided with a lever 25 which serves as an operating member for turning the nut on its threaded bearing. The inner end of the nut bears against a flange 26 formed on the winch drum whereby in the inward move-

ment of the threaded thrust nut the drum will be forced laterally into wedging engagement with the tapered friction blocks, thus clutching the frame to the gear wheel 15. The flange 26 is provided with a bearing sleeve 27. Between the flange 18 and the hub of the gear wheel 15 which drives the drum is a spring 28 which is adapted to force the drum laterally in order to release it from the wooden friction blocks when the thrust nut is turned to the left. When the wooden friction blocks wear, the thrust nut may be moved farther out on its threaded bearing and the adjustable clamp 24 for the clutch lever may then be adjusted to the proper position so that the operating lever may be in the desired position of convenience for the operator.

Projecting laterally from the flange 18 is a circumferential flange 29 against the outer surface of which is adapted to bear a suitable brake band 30, which is adapted to be contracted to apply a braking pressure to the drum by means of bell crank 30' connected to a foot lever 31. When it is desired to connect the winch drum with the power of the engine to lift and lower or otherwise utilize power, the clutch lever is turned so as to move the thrust nut against the drum and carry the latter laterally into driving frictional engagement with the wooden friction blocks. To stop the rotation of the drum and to hold a lifted load suspended or maintain the strain on the operating cable that may be applied to the drum, the brake is applied to the drum by the foot lever and the clutch thrown out and the load held stationary or gradually lowered by controlling the extent of the braking action against the drum.

On the left hand drum flange 26 is attached a ratchet 32 adapted to be engaged by a pawl 33 fixed to the frame whereby the drum may also be held in any desired position if both the clutch and brake have been released.

While the construction just described is illustrative of an arrangement in which only one winch or drum is employed, the particular form of winch supporting frame and

arrangement of the driving gears is such that an auxiliary and interchangeable upper drum may be utilized and the drawings show this auxiliary drum. In this arrangement, 34 is the auxiliary drum which is adapted to be mounted on an auxiliary frame comprising upright side members 35, each of which is mounted on a corresponding side frame member 2 of the main winch frame, the latter side members being preferably composed of angle irons to suitably support the auxiliary side frame members, the two frames being secured together by means of bolts 37. This auxiliary drum is provided with a driving gear wheel 38 adapted to engage the gear wheel 15 and it is also adapted to be provided with friction drive blocks and with a thrust nut similar to that described with reference to the main drum. An operating lever 39 is adapted to control this thrust nut. A foot brake lever 40 is also provided for the upper drum and is adapted to control the operation of a brake for the latter through a rod 41 connected to bell crank 42 similarly to the construction described with respect to the lower drum. Details of these controlling mechanisms are not specifically shown in the drawings since they are identical with those heretofore described with respect to the main drum.

What we claim is:

The combination with a tractor having an axle housing, a winch attachment including a frame having forward supports on the axle housing, a draw bar, said frame having support at its rear end on the draw bar, a winch drum and its operating mechanism carried by said frame, a supplemental frame detachably connected to the first mentioned frame, an auxiliary drum carried by the supplemental frame, driving connections between the first mentioned drum and the tractor and driving connections between the two drums.

In testimony whereof we affix our signatures.

JAMES N. ALLENSWORTH.
MOODY C. KELTNER.
OLIN C. COLLINS.
